(57) **CLAIM**

I claim the ornamental design for a pull tab lid, as shown and described.

DESCRIPTION

FIG. 1 is a perspective view of a pull tab lid.

FIG. 2 is a front plan view of the pull tab lid, which is identical to a rear plan view.

FIG. 3 is a right perspective view of the pull tab lid, which is identical to a left perspective view.

FIG. 4 is a top plan view of the pull tab lid, looking down into its interior; and,

FIG. 5 is a bottom plan view of the pull tab lid.
